NOVELTY

Jasper Likes, Long Beach, Calif.

Application February 24, 1936, Serial No. 65,461

2 Claims. (Cl. 46—135)

This invention relates to a novelty of the dancing figure type and has for the primary object the provision of a device of this character which will be inexpensive to make and simple 5 to operate and will readily attract attention and afford amusement.

With these and other objects in view, this invention consists in certain novel features of construction, combination and arrangement of 10 parts to be hereinafter more fully described and claimed.

For a complete understanding of my invention, reference is to be had to the following description and accompanying drawing, in which

15 Figure 1 is a front elevation illustrating a novelty constructed in accordance with my invention.

Figure 2 is a sectional view taken on the line 2—2 of Figure 1.

20 Figure 3 is a rear elevation illustrating the device.

Figure 4 is a sectional view taken on the line 4—4 of Figure 1.

Referring in detail to the drawing, the numeral 1 indicates a support of panel formation and is provided with pairs of openings 2 and 3. Arranged in front of the panel 1 is a figure 4 of any desired design. The figure 4 includes a body 5, head 6 and hips 7. The body 5 has the usual shoulders 8. Pairs of plates 9 and 10 are secured to the front face of the panel 1 and extend over the pairs of openings 2 and 3 and spaced therefrom. Each plate 9 is in the form of a hand, while each plate 10 is in the form of a foot. The plates 9 and 10 are non-movable 35 relative to the panel 1, while the figure 4 is movable relative to said panel. Pairs of flexible strips 11 and 12 are secured together, as shown at 13, to form a finger piece. The strips 11 extend through the openings 2 and are secured to the shoulders 8 of the body 5. The pair of strips 12 extend through the openings 10 and are secured to the hips 7 of the body 5. The

strips 11 where extending from the shoulders 8 to the plates 9 represent arms while the strips 12 where extending from the hips 7 to the plates 10, represent legs. The hand piece 13 is arranged at the rear of the panel 1.

In operation, the panel is positioned to place the figure 4 in view to an onlooker and the operator grasps the finger piece 13 and imparts movement thereto which causes the figure 4 to move over the panel with movements simulating dancing of the figure. The finger piece 13 may be moved in different directions which will cause the figure 4 to move upwardly and downwardly and sideways with respect to the panel, giving the observer the impression that the figure 4 is dancing, also giving an impression of the shortening and lengthening of the arms and legs during certain movements of the figure. Thus it will be seen that a figure novelty of this kind is simple, durable and easy to operate and may be manufactured and sold at a low cost.

Having described the invention, I claim:

1. A novelty comprising a panel having openings, a figure positioned over one face of the panel, and including head and body portions, and an operating means actuated from the other face of the panel and extending through the openings and connected to the body portion for supporting the figure adjacent the panel free to move relative thereto and providing arms and legs for the body portion of the figure.

2. A novelty comprising a panel having openings, a figure disposed over one face of the panel, plates secured to said face of the panel and overlying and spaced from the openings and shaped to form feet and hands, and connected strips extending through the openings and secured to the figure to represent legs and arms between the figure and the feet and hands and when moved by the connected portions adapted to impart dancing movements to the figure.

JASPER LIKES.
